Inventor
William H. Cooke,
by Emily South Janney Cooke

UNITED STATES PATENT OFFICE.

WILLIAM H. COOKE, OF DORCHESTER, MASSACHUSETTS.

ARCH-SUPPORTING MEMBER.

Application filed January 31, 1920. Serial No. 355,352.

To all whom it may concern:

Be it known that I, Dr. WILLIAM H. COOKE, a citizen of the United States, and resident of Dorchester, Boston, county of Suffolk, and State of Massachusetts, have invented an Improvement in Arch-Supporting Members, of which the following description, in connection with the accompanying drawings, is a specification, like characters on the drawings representing like parts.

This invention has reference to boots and shoes and particularly to the construction of the sole thereof, and its object is to provide a sole that will, by furnishing suitable support for the foot, prevent the breaking down of the metatarsal arch and consequent loss of leverage or pull exerted by means of the toes when the arch and toes are in normal positions.

In the drawings of one embodiment of my invention which is here illustrated for a better understanding of the same,

Fig. 1 is a plan of my novel arch supporter;

Fig. 2, a plan of a sole embodying my supporter;

Fig. 3, a cross-section thereof on the line 3—3 Fig. 2, showing also in cross-section a conventional representation of the bones of the foot forming the metatarsal arch in natural position; and

Fig. 4, a similar view showing the arch broken down and the bones forming the same in the abnormal position frequently found to exist.

It is well known that the principal bones of the foot forward of the instep arch, are those forming the metatarsal or anterior arch. Referring to Fig. 3, the bones 1, constituting the arch of the foot *a* are shown in their natural and upwardly arched positions and, when so positioned, perform primarily the function of supporting the foot structure. The bones constituting the toes or phalanges 45 extend forwardly from the metatarsal arch and, when the arch and toes are in proper position, permit the person to exert a pull or leverage by means of the tendons and muscles which enables him to walk readily and without undue fatigue.

When, however, from accident or any other cause, this metatarsal arch breaks down

as illustrated in Fig. 4, the support usually furnished by the arch is of course gone, the weight of the body is imposed unnaturally upon the foot in such manner that it cannot support the body without undue strain, and the ligaments or tendons connecting the phalanges to the metatarsal arch become strained, while the ends of the toes, instead of turning naturally downward or lying flat are turned slightly upward. The result of this condition is that the person is unable to exert the pull or leverage by means of the toes which is normally so exerted, and walking as well as standing, therefore becomes fatiguing and laborious.

It has sometimes been attempted to correct this abnormal condition of the bones forming the metatarsal arch and the consequent abnormal position of the toes by inserting within the shoe material for building up a supporting section for the arch, but such measures have been only partially successful. In any event it is merely an attempt to cure the abnormal condition after it has once materialized. My invention is calculated to be used in a sole under ordinary conditions while the foot is in its normal position and thus make it practically impossible for the arch to drop down in the manner described.

Referring to Fig. 3, my novel shoe may comprise the usual outer sole 2, welt 3, filler 4, and insole 5. The filler commonly employed is preferably of somewhat plastic material which stiffens gradually and fills up the space between the two soles and the welt and prevents squeaking of the shoe as for instance, the filler described in United States Letters Patent No. 832,002 issued September 25, 1906 to Andrew Thoma, which I have found to answer my purpose very satisfactorily.

In the ordinary process of shoe making after the filler has been put on the insole, I find it convenient to place near the top of the filler or within the same an arch supporting member 6 which may be of any convenient outline, but preferably curvilinear, and convex in vertical cross-section, Fig. 3, made of any suitable material such as rubber compound, paper, paper board, leather, or leather board properly stiffened, or even

some soft metal sufficiently rigid to give the necessary support to the foot when it is flattened out. This member is substantially of the size to provide desired support for the foot that the particular shoe is designed generally to fit.

Preferably however, the arch supporting member 6 is embedded in some material as a filler which will permit the support to yield somewhat laterally if the contour of the foot to be supported requires it, until it reaches the proper position that is required for that particular foot in case of course, it fails to do so as originally positioned.

The filler is generally more or less sticky, and therefore usually the outer convex surface or wall of the arch supporting member readily adheres sufficiently to the filler to preliminarily anchor the member which, however, becomes permanently anchored in time by the hardening of the filler about it. In case the filler used should not be sufficiently adhesive, of course an additional adhesive element of some suitable kind may be used.

After the shoe has been worn a short time the warmth of the foot softens the filler, if it has previously hardened, sufficiently to permit limited bodily adjustment of the supporter to enable it to occupy the position that it naturally tends to do under the pressure of the foot. When thus supported, the arch cannot ordinarily break down and the cause of the trouble is avoided. Obviously, if a filler other than the plastic filler is used, such as a sheet of leather or suitable material, the arch supporting member may be secured thereto or therein by any suitable means.

Obviously my invention is not limited to the precise embodiment illustrated and described herein, and I claim:

1. The combination with a shoe having an outer sole and an inner sole, of a plastic filler between the soles, a movably attached disc-like arch supporting member on the filler, and adapted, under pressure and warmth of the foot, to position itself at a point where the lateral pressure is substantially equalized.

2. The combination with a shoe having inner and outer soles, of a yielding filler between the soles, and an arch supporting member preliminarily anchored in the filler and adapted upon softening of the filler and under foot pressure to adjust itself to permanent anchorage.

3. The combination with a shoe having inner and outer soles, of a yielding filler between them, an arch supporter adhesively mounted on the filler and adapted under pressure of the foot to move on said filler.

4. The combination with a shoe having inner and outer soles, of a yielding filler,

and an arch supporter floated thereon movable under the influence of heat and foot pressure.

5. A shoe comprising an outer sole, a filler, an inner sole, and an arch supporting member permanently incorporated between the filler and the inner sole forward of the shank movable as a unit laterally under the influence of foot pressure.

6. A shoe having an upper and an insole, and beneath the latter a laterally yieldable filler, and an arch supporting member thereon constructed and arranged to position itself laterally beneath the metatarsal arch to support the same.

7. The combination with a shoe having a member providing a supporting surface for the sole of the foot and means for retaining said member on the foot, of separate means adapted to provide a localized elevation of said sole supporting member forward of the shank, said elevation means being adhesively held to the sole supporting member while responsive as a unit under the pressure and action of the foot and thereby caused to register itself laterally with an arch of the foot.

8. The combination with a shoe having a sole and an insole, of a convex metatarsal arch supporting member disposed between the sole and the insole, a layer of heat responsive filler holding the arch supporting member to the sole, said member being free to cooperate with the foot to work into position for registering with said arch of the foot.

9. The combination with a shoe having a sole and an insole, of an arch supporting member movably floated between the sole and the insole forward of the shank, at least a portion of the upper face of said member having a convex formation and being adapted to elevate the overlying portion of the insole.

10. The combination with a shoe having a sole, an insole and a plastic filler between the sole and the insole, of a convex member arranged between the sole and the insole and movably carried on the filler, said member being constructed and arranged to cooperate with the movements and pressure of the foot to work into registering position for supporting the arch of the foot.

11. A shoe having the outer sole 2, inner sole 5, and means for raising the inner sole at a point beneath the metatarsal foot arch comprising the filler 4 between the soles and the arch supporting member 6 floated on the filler 4, and movable under the influence of heat and foot pressure to a point beneath the metatarsal arch.

12. A shoe having an outer and an inner sole, a laterally movable filler between them, and an arch supporting member movably carried by said filler, and constructed and

arranged to position itself under the influence of foot pressure to raise the inner sole beneath the metatarsal arch. under the influence of foot pressure and warmth from the foot to position itself laterally beneath an elevated portion of the 10

13. A shoe having an outer and an inner sole, a paste like filler between them, and an arch supporting member adhesively connected to the filler and movable thereon In testimony whereof, I have signed my name to this specification.

WILLIAM H. COOKE.
